BUFFING WHEEL

Arthur B. Stafford, Forest Hills, N. Y., assignor
to Ajax Buff Company, Chicago, Ill., a corpora-
tion of Illinois

Application August 24, 1948, Serial No. 45,946

5 Claims. (Cl. 51—193)

1

This invention relates to a buffing wheel and method of making the same, and more particularly to a buffing wheel in which a cloth buffer is adapted to be rotatably disposed on a shaft by means of a hub assembly to present a flexible buffing surface, and to methods for making such buffing wheels.

Cloth buffing wheels, as heretofore employed, comprise generally an annular buffer formed of a plurality of fabric layers secured to a hub. In one common form, the hub construction consists of a pair of annular rings adapted to be mounted on either side of the buffer, each of the rings being provided with sharpened teeth about its outer periphery. These teeth are bent inwardly toward each other to bite into the cloth layers without passing entirely through the buffer to maintain the cloth layers in position about the rings. A separate, centrally apertured circular plate, sized to fit tightly within one of the annular rings, is adapted to be mounted on a shaft or arbor. A pair of separate embossed mounting disks, of a diameter approximately equal to that of the annular ring, are provided to abut either side of the circular plates to maintain the complete buffing wheel in position upon a shaft or arbor.

The disadvantages residing in the complicated buffing wheels heretofore employed have been appreciated by those skilled in the art, and many attempts have been made to provide more simple buffing wheel structures. However, the expedients of the prior art have proven unsatisfactory because of their complexity, the expense of making the hub assembly, and the difficulty of firmly securing the cloth buffing layers to the hub.

The present invention now provides an improved type of buffing wheel in which a cloth buffer is secured to a wheel hub by positive clamping means. The buffing wheel of the present invention is simple in design and manufacture, and the cloth buffer is securely clamped within the wheel assembly by means of the improved form of hub herein provided. Further, the wheel of this invention eliminates the separate circular plates and securing disks of the prior art by providing shaft mounting means formed integrally with the clamping members of the wheel assembly and adapted to cooperate with a pair of mounting flanges for disposing the buffer on a rotatable shaft.

The cloth buffer of the buffing wheel of the present invention may be selected from the numerous types of buffing wheel cloth constructions well known in the art, although I prefer to em-

2

ploy buffers formed from a plurality of superimposed layers of elongated, bias-cut strips, gathered or pleated transversely and sewed longitudinally down the center. The strips are then folded into an annular configuration presenting free edges forming the actual buffing surface.

The hub assembly of the buffing wheel of the present invention comprises generally a mounting plate adapted to overlie one side surface of the annular buffer in a position adjacent the inner periphery of the buffer. The plate is provided with a centrally located aperture defined by an integral cylindrical flange and a plurality of projections or teeth formed about its outer periphery. The teeth of the plate are deformed to lie approximately normal to the plane of the disk and adapted to be passed through each layer of the buffer to project therebeyond. A ring, provided with circumferentially disposed apertures adapted to receive the teeth of the disk projecting beyond the side surface of the buffer, overlies the opposing side surface of the buffer and cooperates with the disk for securely clamping the buffer within the buffing wheel assembly. The plate teeth are deformed to lie against the surface of the ring to maintain the cloth buffer tightly clamped in position between the disk and the ring. The assembled, complete buffing wheel may then be mounted in a suitable manner upon a shaft or arbor by means of the centrally located plate aperture strengthened by the cylindrical flange.

It is, therefore, an important object of the present invention to provide an improved buffing wheel of simple design and manufacture in which a cloth buffer is secured to a pair of clamping members disposed on either side of the buffer and adapted to be mounted on a shaft or arbor.

It is another important object of the present invention to provide a buffing wheel comprising a cloth buffer, a clamping plate overlying a portion of one side surface of the buffer, a ring overlying an opposed side surface of the buffer, and clamping means carried by the plate and extending through the buffer into surface engagement with the ring to clamp the buffer between the plate and the ring.

It is still another important object of the present invention to provide an improved hub assembly for a cloth buffing wheel including a circular plate and an annular ring adapted to overlie opposed sides of a buffer and interlocking means carried by the disk and the plate and extending completely through the buffer for securing said buffer in position therebetween.

It is a yet further important object of the present invention to provide a method of making a buffing wheel comprising the stamping of sheet metal to provide a disk having peripheral teeth and a metal ring having apertures corresponding to the teeth of the disk, bending the teeth at approximately 90° to the plane of the disk, positioning the disk and the ring on opposite sides of a cloth buffer, forcing the teeth through the buffer and the corresponding apertures formed in the ring, and bending the teeth against the surface of the ring to lock the buffer in position therebetween.

On the drawings:

Figure 1 is an elevational view of a clamping member of the buffing wheel of the present invention;

Figure 2 is a sectional view taken along the plane II-II of Figure 1, showing in dotted outline a deformed position of the clamping member teeth;

Figure 3 is an enlarged, exploded sectional view showing the relative position of the clamping members prior to the assembly of the buffer and the members;

Figure 4 is an enlarged sectional view similar to Figure 3, showing the relative position of the buffer and clamping members following assembly;

Figure 5 is an elevational view, with parts cut away, of a buffing wheel of the present invention; and

Figure 6 is a sectional view, with parts shown in elevation, of a plurality of buffing wheels disposed on a shaft.

As shown on the drawings:

Reference numeral 10 in Figures 5 and 6 refers generally to a buffing wheel of the present invention comprising a cloth buffer 11, a circular disk 12 and an annular ring 13.

As best shown in Figures 1 and 2, the disk 12 is generally circular in outline and is provided with a centrally located, integrally formed cylindrical flange 14 defining an aperture 16 concentric with the disk. An interior annular portion 16 of the disk 12, immediately surrounding the flange 14, is provided with a plurality of elongated, radially extending reinforcing ribs 17 symmetrically disposed about the flange 14. The outer peripheral portion 19 of the disk 12 is offset axially from the mean plane of the disk 12 as shown in Figure 2 with the portion 19 being joined to the interior portion 16 by an integral slanted annular portion 18. A plurality of radially extending teeth 20 are formed integrally with the disk 12, the teeth being uniformly and circumferentially disposed about the outer disk portion 19. The teeth 20, prior to assembly of the buffing wheel 10, are bent or deformed approximately 90° from the mean plane of the disk to surround the flange 14, as shown in dotted outline in Figure 2.

As may be seen from Figures 3-6, inclusive, the annular ring 13 is of slightly smaller outside diameter than the outside diameter of the disk 12 and is of approximately the same inside diameter as the annular buffer 11. The ring 13 is provided with a plurality of circumferentially spaced apertures 21, corresponding in location and approximate size to the teeth 20 deformed as in Figure 3. The inner peripheral portion 22 of ring 13 is axially deformed, as in Figure 3, for a purpose to be hereinafter described. The simple design of the disk 12 and the ring 13 makes possible the economical and expeditious manu-

facture of the buffing wheel of the present invention. For example, it is possible to stamp each of these clamping members from sheet metal by a single operation.

As has been hereinbefore explained, the cloth buffer 11 may be any of the numerous types of the annular buffing cloth constructions known in the art. However, it is preferred that annular buffers formed of a plurality of elongated bias cut strips be employed. Such buffers are generally prepared by transversely gathering or pleating a plurality of superimposed strips, sewing the strips longitudinally down the center as at 11a in Figures 3 and 4 and then doubling the strip upon itself along the sewed line. The doubled strip is then folded or pleated into an annular configuration having a smooth generally rounded inner periphery 11b to fit the buffing wheel hub assembly.

As shown in Figure 3, the assembly of a cloth buffer on the hub may be easily accomplished by positioning the disk 12 and the ring 13 on opposite sides of the buffer 11 and forcing the teeth 20 through the cloth buffer 11 and the apertures 21, so that the end portions 20a of the teeth project beyond the annular ring 11. Following the passing of the teeth through the buffer and the ring apertures 21, the end portions 20a of the teeth are bent inwardly to lie against the outer surface of the ring 13. It will be seen in Figure 4 that the buffer 11 is securely retained between the disk 12 and the ring 13. The inner periphery 11b of the buffer 11 contacts the converging surfaces 22 and 18 as shown in Figure 4, while the adjacent side surfaces of the buffer 11 are supported by the surface 18 and the ring 13 bearing thereagainst. Further, the annular buffer 11 is completely pierced by each of the teeth 22 to securely retain the buffer in position within the hub assembly.

The teeth formed integrally with the disk and deformed against the ring provide a plurality of positive gripping elements spaced circumferentially about the entire inner peripheral portion of the buffer to tightly maintain the buffer in position within the buffing wheel.

If desired, the design of the clamping members 12 and 13 may be simplified by straightening the slanted annular portion 18 and the axially deformed portion 22. All portions of each member thus lie in a single plane, with the exception of reinforcing ribs 17 of disc 12 and the teeth 20 when deformed as shown in Fig. 3. The clamping members thus formed contact only the sides of buffer 11 rather than the sides and inner periphery, as in Fig. 4.

Due to centrifugal forces set up during rotation of the wheel, a radially outward force will be exerted on the buffer and this force will be transmitted to that portion of the teeth 20 passing through the buffer 11. Any deformation of the teeth under this stress will tend to pull the clamping members 12 and 13 more tightly against the buffer sides. Thus the centrifugal forces set up during the operation of the wheel increase the clamping of the buffer between the clamping members.

Another advantage of the present invention resides in the possibility of employing buffers of any desired thickness by merely changing the length of the teeth 20.

During the use of the buffing wheel of the present invention, a considerable amount of heat is generated at the cloth buffing surface. This heat tends to pass to the center of the wheel where it is readily dissipated by the large, heat conductive

mounted on certain other supports and so position the surface area of the disc. The passage of heat from the buffer to the disc is facilitated by the design of the buffer herein described, since no heat conductive material is interposed between the buffer and the disc and further since the disc itself is metallic and of thin cross-section to present a very efficient heat dissipating surface to the surrounding atmosphere.

As shown in Figure 6, a plurality of buffer wheels of the present invention may be mounted on a shaft or arbor, such as shaft 23, by means of the flange 14 formed integrally with the disk of each buffering wheel. The shaft 23 is provided with an integral enlarged shoulder 24 against which a mounting flange 25 is placed. Flange 25 is of approximately the same diameter as ring 13 and is provided with a central cylindrical flange 25a defining an aperture 25b sized to receive shaft 23 therethrough. Following the positioning of flange 25 on the shaft 23 to abut shoulder 24, a plurality of buffer wheels 10 are placed on the shaft with the circular lip of the flange 14 of the innermost buffer wheel 10 abutting the lip of flange 25a. The remaining buffer wheels are then placed on the shaft 23 with the deformed portion 20a of the teeth 20 abutting the exterior surface 19 of the adjacent wheel 10 and the apertures 15 receiving the shaft 23. Following the assembly of the desired number of buffering wheels on the shaft 23 a second flange 25 is placed against the exposed surface of the outer buffering wheel with the lip of its flange 25a abutting the central portion of the outermost disc 12 and its outer peripheral portion abutting the outer periphery of disc 12. A nut 26 is screwed upon the threaded outer end of the shaft 23 to maintain the assembled flanges 25 and buffering wheels 10 on the shaft. The buffering wheels thus arranged to form a larger unit may then be employed in a conventional manner for buffering any desired surface.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A buffering wheel comprising a cloth buffer formed of a plurality of fabric layers pleated, sewn and folded into an annular configuration, a circular disk and an annular ring having their outer peripheral portions overlying opposed side surfaces of said buffer, said disk having circumferentially spaced teeth formed in its periphery and being centrally apertured to receive a shaft, said ring having circumferentially spaced apertures corresponding to said teeth, said teeth extending normally from said disk through each of said layers and said ring apertures and being deformed to lie against the outer surface of said ring, said teeth thus securing said ring, said plate, and said buffer against both radial shifting and axial separation.

2. A buffering wheel comprising a cloth buffer and a pair of clamping members having por-

tions overlying opposed side surfaces of said buffer, one of said members having spaced teeth on its outer edge and the other of said members having spaced apertures corresponding to said teeth, said teeth extending through said buffer and the apertures in said second member and being deformed to lie against the outer surface of said second member to retain said buffer between said members against both radial shifting and axial separation.

3. In a buffering wheel having a cloth buffer mounted between opposed supporting members, means for maintaining said buffer in position between said members comprising spaced teeth formed on one of said members and extending completely through said buffer, said second member having spaced apertures formed therein corresponding to said teeth on said first member and adapted to receive said teeth therethrough, said teeth being deformed against said second member to securely clamp said buffer between said members against both radial shifting and axial separation.

4. In a buffering wheel having a cloth buffer formed of a plurality of fabric layers, means for maintaining said layers in operable position upon a rotatable shaft comprising a disk and an annular ring having their outer peripheral portions overlying opposed side surfaces of said buffer, said disk having circumferentially spaced teeth formed in its periphery and being apertured to receive the shaft, said ring having circumferentially spaced apertures corresponding to said teeth, the teeth extending from said disk at right angles to the plane of the disk through said buffer layers and said ring apertures and being deformed to lie against the outer surface of said ring said teeth thus securing said ring, said plate, and said buffer into an integral assembly and preventing both radial shifting and axial separation.

5. A buffering wheel comprising a cloth buffer and a pair of clamping members having portions overlying opposed side surfaces of said buffer, one of said members having integrally formed pointed projections extending completely through said buffer into interlocking engagement with the other of said members to secure said buffer in position between said members, said pointed projections thus preventing both radial shifting and axial separation of said members and said buffer.
